Application December 27, 1933, Serial No. 704,127

9 Claims. (Cl. 110—32)

My invention relates to improvements in combustion apparatus such as coal-burning furnaces. The principal object of the invention is to provide an improved automatic operating and control system for such coal-burning furnaces or boilers, and more particularly as applied to existing types of furnaces or boilers.

A further object is to provide light-actuated means by which the system is controlled, to give simplicity and improved economy of fuel and electric current.

Other objects will appear in the following description.

Referring to the drawings:

Fig. 1 is a diagrammatic view of my system applied to a coal-burning boiler of known type;

Fig. 1a is a fragmentary view of the system shown in Fig. 1, one of the elements of the system being illustrated in detail.

Fig. 2 is a fragmentary section of the grate operating mechanism, ash pit, and light-sensitive control device;

Fig. 3 is a detail view of the shaker eccentric mechanism;

Fig. 4 is a vertical section of the friction drive coupling; and

Fig. 5 is a diagrammatic view of an alternative form of the system shown in Fig. 1.

The numeral 10 denotes an automatic fuel feed coal-burning boiler of known type, having a fuel hopper 11 from which fuel descends by gravity through a funnel 12 to a pair of sloping grates 13 and 14, when the latter are shaken. The numeral 15 denotes the ash pit which is provided with the usual doors 16 and 17. A light-responsive device 18, of well-known commercial form, is suitably mounted near the top of the ash pit 15 in such manner that its sensitive side is directed into the pit, so that it may be actuated by the light of live coals in the pit.

A cross shaft 19, journaled in brackets 20 fixed to the boiler 10, is provided with eccentrics 21 which are positioned in line with the usual shaker levers 22 of the grates 13 and 14. Forks 23, fastened to the shaker levers 22 by any suitable means, such as set screws 24, engage grooved sleeves 25 rotatably mounted in the eccentrics 21.

The numeral 26, Fig. 2, denotes a typical unit of the grate 13, the unit 26 having a downwardly extending lever 27 and a rocker pin or axis 28. A bar 29 pivoted to all levers 27 is articulated to the shaker lever 22 at the front of the furnace 10, this internal shaker mechanism being old and well-known.

The numeral 30 denotes an electric motor adapted to drive the shaft 19 through a worm and gear speed-reducer 31, or other suitable means, and a safety coupling 32.

Referring to Fig. 4, the numeral 33 denotes a driving cup fixed to the driven shaft 34 of the

speed-reducer 31. A driven flange 35 is fastened to the shaft 19. A presser ring 36 slidable in the cup 33 is urged into the latter by springs 34a under adjusting nuts 36, gripping the driven flange 35 between a pair of friction rings 37 and 38a.

Referring again to Fig. 1, the numeral 39 denotes a relay of well-known form, adapted to be controlled by the light-sensitive device 18 through an amplifier 18a. A magnetic switch 40, preferably of the known type embodying a thermal overload protective device, is adapted to make or break the main electrical connections between the motor 30 and a main source of supply current 41.

Referring to Fig. 1a, a conductor 42 extends from relay 39 to switch element 80 of magnetic switch 40. The switch 80 is normally restrained against movement under the influence of spring 81 by a bi-metallic thermal element 82 anchored at 83. In its normal, or restrained position, switch 80 establishes a circuit through conductor 42 to a solenoid 85, thence to the positive terminal of the source of electrical energy 41, through conductor 47. Thus a circuit is completed from the negative terminal of the power source 41, through time clock 43, conductor 46, relay 39, conductor 42, magnetic switch 40, and finally to positive terminal 41. When a circuit is thus established, solenoid 85 operates plunger 86, and link 87, to close switch 88 against the action of spring 89 thereby making a circuit to motor 30 through conductors 48 and 49. A heating coil 90 underlying the thermal element 82 will be seen to be connected in series relation with switch 88 and conductors 48 and 49 to motor 30.

The timing mechanism of the clock 43 may be of the well-known electrically operated type, such as are shown in U. S. patents to Warren, #1,262,575; #1,522,988; or #1,533,677. A supply circuit 45 is provided to run the clock; and the clock is provided with the usual devices for turning on and off the control circuit to conductor 46 at any desired times and intervals.

The operation of the device as shown in Fig. 1 is as follows: At a predetermined time in the morning, the clock 43 closes the circuit to conductor 46, the relay 39 being in closed position. The switch element 88 of the magnetic switch 40 is thereby closed, thus starting the motor 30 by the current from the main line 41, and revolving the shaft 19. The eccentrics 21, through the sleeves 25, oscillate the forks 23 and the levers 22, thereby reciprocating the bars 29 and rocking the grate units 26. This causes the ashes to drop into the ash pit 15, fresh coal descending from the hopper 11. The shaking action normally continues until live coals drop into the pit. When this occurs, the light-sensitive device 18 is energized, causing it to open the relay 39, 60

and thereby break the control circuit 46. This causes the magnetic switch 40 to break the main circuit 41, thus stopping the motor 30, and stopping the grate-shaking action.

5 To provide for the contingency that live coals might not appear within a given time (as would be the case if the fire should be out) the clock 43 can have its circuit-breaking device set for a short time interval beyond the circuit-breaking 10 position, so that the shaking action could thereby be limited in time, independently of the action of the light-sensitive control.

When the fire has been shaken until live coals appear in the pit, the circuit is then held open by 15 the light-sensitive device 18 so long as the glow remains. As soon as the glow ceases, or dies down enough to permit the device 18 to stop functioning, the relay 39 again closes. Therefore if the circuit at the time clock is still closed, 20 the shaking will begin again, to continue until new live coals operate the device 18 to stop the shaking.

But if meantime the elapsed time is such that the time clock has now reached its circuit-opening 25 position, then the shaking action cannot begin again until the clock reaches a new, predetermined time-point, at which time the clock is set for a renewed making of the circuit for grate-shaking purposes. Thus, this setting of the circuit 30 making and breaking devices in the clock 43 may be predetermined at whatever proves to be the suitable periods for use.

In case a grate should stick, tending to stall the motor 30, the flange 35, (Fig. 4), slips between the friction rings 37 and 38a, but the motor, of course, draws a heavier current than is normally required. If the stoppage or retarding effect should be only momentary, the excess current is not maintained long enough to actuate the 40 thermal release and as soon as the retarding force subsides, the friction surfaces once more grip the flange 35 and the shaking of the grate is resumed. If the stoppage continues, the safety coupling continues to slip and the motor continues to draw excessive current until the thermal protective device in the magnetic switch 40 comprising the heating coil 90, thermal element 82 and spring 81 heats up and opens the motor circuit, after which the obstacle is removed manually and the thermal device reset in the usual 45 way.

The drawings illustrate a boiler with two grates. Should it be desired to operate only one grate, the fork 23 may be removed from its lever 22 by 50 loosening the screw 24.

While a particular kind of boiler and grate are illustrated, it should be understood that the illustrations are purely typical and the device can be applied to any desired furnace or boiler 55 having a suitable shaker grate or grates.

Referring to Fig. 5, in which an alternative embodiment of the invention is disclosed, the time clock 43' will be understood to be identical in all respects with the clock 43 of Fig. 1, but is shown in greater detail to facilitate an understanding of the operation of the system. Similarly, the magnetic switch 40' is preferably identical with the switch 40 of Fig. 1, but like the time clock 43' is illustrated in greater detail to more 60 clearly disclose the operation of the system. The light sensitive cell 18', amplifier 18'a and relay 39' will likewise be understood to be identical with the corresponding elements of Fig. 1. This particular embodiment of the invention contemplates a system in which the time clock functions

to establish the circuit to the stoker operating motor at predetermined intervals, as is the case in the disclosure of Fig. 1, but it is anticipated that under some conditions of operation it may be desirable to intermittently make and break the 5 circuit to the stoker driving motor during periods when the time clock functions to constantly operate the latter.

To this end, a time limit switch 50 is interposed in the circuit between the time clock 43' and the 10 driving motor 30' of the grates. As shown, the time limit switch 50 comprises a motor 51 arranged to rotate a gear 52 rigidly connected to a cam 53 which in turn is adapted to operate a switch arm 54, connected in series with relay 39'. 15

Spring 54' normally tends to open a circuit from the time clock 43' through conductor 55, thence to relay 39' and magnetic switch 40' to motor 30' thus preventing operation of the stoker. For a more complete description of the 20 50 reference may be had to pages 66 to 68 of "Machine Design," of June, 1930, published by the Johnson Publishing Company, Penton Building, Cleveland, Ohio.

Now considering the cooperative functions of 25 time clock 43' and time limit switch 50: The time clock is permanently connected to the source of electrical energy 41' by lead wires 45' to constantly operate the clock motor 60. The motor 60 rotates a dial 61 provided with angularly adjustable, on and off riders, 62 and 62a respectively. It will be understood that these riders may be positioned on dial 61 at any desired points corresponding with the particular hour or time when it is desired to complete or 30 interrupt a circuit to motor 51 of time limit switch 50, and thus effect intermittent operation of the stoker motor 30'. The riders 62 and 62a are arranged to contact a laterally protruding knob 62b of a switch arm 63 which is maintained 40 in "on" and "off" positions by a spring actuated toggle 62c. A mercury reservoir 64, rigidly connected to switch arm 63 is provided with electrodes as shown, to complete a circuit from power source 41' through conductors 65 and 66 to 45 motor 51 when switch arm 63 occupies the position shown in Fig. 5. Arm 63 is rocked to the position of Fig. 5 by the "on" rider 62 and is adapted to be moved in a clockwise direction to its "off" position by rider 62a which cams the 50 knob 62b downwardly as dial 61 rotates in a clockwise direction.

As will be apparent, the circuit from conductor 55 leads through switch 54 relay 39' and thence to magnetic switch 40' through conductor 70. 55 Magnetic switch 40' is, as has been pointed out, identical with the switch 40 of Fig. 1a. Briefly, the conductor 70 is connected to a switch arm 78, which is normally restrained from movement under the influence of a spring 77, by a thermal element 76 one end of which is anchored to the base of magnetic switch 40'. When thus restrained, switch 78 establishes a circuit through conductor 72 to solenoid 71 and then back to the negative terminal of power source 41'. Thus 60 65 solenoid 71 operates to close switch 73 thereby completing a circuit through heating element 75 to motor 30'.

The time limit switch 50 will operate to alternately make and break the circuit to motor 30' 70 during any period of time when switch arm 63 of clock 43' is in its "on" position. The duration of the operating and idle periods of the stoker motor may be modified by replacing the cam 53 with others of differing configuration. Cams of 75

this character are commercially available for time limit switches of the type of switch 50 so as to produce cyclic operations of the following sequences:

	Total time cycle	Circuit closed
	5 minutes	3 seconds to 3 minutes.
	15 minutes	9 seconds to 9 minutes.
	30 minutes	18 seconds to 18 minutes.
	1 hour	36 seconds to 36 minutes.

By utilizing the time clock 43 for the main turning on of the circuit in the morning and turning off at night, the time limit switch 50 can be made use of for the shorter intervals of turning the current on and off, such as might be suitable for ensuring the proper shaking of the grate at such times as might be necessary.

It will be noted that the thermal overload devices of magnetic switches 40 and 40' will be effective to break the circuit to the stoker motor in the event that the thermal elements 82 or 76 respectively are caused to move to the dotted line positions shown as a consequence of overheating of the respective coils 90, or 75.

What is claimed is as follows:

1. In a furnace control, the combination with the shaker mechanism of a furnace, and an electric motor and circuit for operating the shaker mechanism, of an electric light-sensitive device located in proximity to the ash pit whereby to be actuated by the light from live coals, a control switch and circuit connected with the light-sensitive device for breaking the electric motor circuit, and a timing device controlling the electric motor circuit to make and break said circuit at selected intervals when the said control switch is in circuit making position.

2. In a furnace control, the combination set forth in claim 1, having in addition thereto an auxiliary timing device operating an auxiliary switch in said electric motor circuit to make and break said circuit at shorter time intervals than the make and break periods of the first mentioned timing device.

3. In a furnace control, the combination with the shaker mechanism of the furnace, and an electric motor for operating the same, of a time-clock-controlled circuit for said motor including a time clock switch in said circuit, an electric light-sensitive device located in proximity to the ash pit whereby to be actuated by the light from the live coals, a circuit for said light-sensitive device including a relay mechanism; a switch opened by said relay and located in said time clock circuit; and switch opening and closing devices carried by said time clock and operating upon said time clock switch to open and close said time clock circuit and thereby stop and start said electric motor at predetermined times when the said relay switch is closed.

4. In a furnace control, the combination set forth in claim 1, and wherein the electric motor is connected to the shaker mechanism by a friction coupling, and the said circuit for said electric motor contains a thermal protective device to open said motor circuit when obstacles located in the shaker mechanism prevent said friction coupling from driving.

5. The combination with a coal burning furnace including a grate, electrical means to actuate said grate, an ash pit below the grate, and a source of electrical energy, of control means to

initiate and terminate operation of the grate actuating means comprising a time sensitive switch connected to said source of energy in series with the grate actuator, a normally closed relay switch in series with said grate actuating means and time switch, and a light sensitive device focused in the ash pit and connected in series with the source of energy, the time switch, and the actuator.

6. The combination with a coal burning furnace including a grate and an electrical actuator therefor, an ash pit below the grate and a source of electrical energy, of control means to initiate and terminate operation of said grate comprising a time controlled switch connected in series with said source of energy and said actuator, a normally closed relay switch in series with the actuator and time switch, and a photo electric cell focused in said ash pit and arranged to open said relay switch as an incident to the falling of live coals from said grate to the ash pit.

7. The combination with a coal burning furnace including a grate and an electrical actuator therefor, an ash pit below the grate and a source of electrical energy, of control means to initiate and terminate operation of said grate comprising a time controlled switch and a time limit switch arranged to jointly and individually control a flow of current from said source of energy to said actuator, a normally closed relay switch in series with the actuator and time switches, and a light sensitive cell focussed in said ash pit and arranged to open said relay switch as an incident to the falling of live coals from said grate to the ash pit, to defeat operation of said first named switches.

8. The combination with a furnace including a grate, an electrical actuator for said grate, and a source of electrical energy; of a time clock in fixed circuit relation with said source of energy, a time limit device, a switch arranged to be controlled by said clock to make and break a circuit from said source of energy to said time limit device, a switch arranged to be operated by said device to make and break a circuit from said source of energy through said first mentioned switch to said actuator, to cycle the latter at predetermined short intervals while the circuit from the first mentioned switch to said device is in circuit making position, a normally closed relay switch in the circuit from said last mentioned switch to said actuator, and a light sensitive cell focussed in said ash pit and connected in circuit with said relay to open the latter as an incident to the falling of live coals from said grate.

9. The combination with a furnace including a grate, an electrical actuator for said grate, and a source of electrical energy; of a time clock in fixed circuit relation with said source of energy, a time limit device, a switch arranged to be controlled by said clock to make and break a circuit from said source of energy to said time limit device, a switch arranged to be operated by said device to make and break a circuit from said source of energy through said first mentioned switch to said actuator to cycle the latter at predetermined short intervals while the circuit from the first mentioned switch to said device is in circuit making position, and a light sensitive cell effective to break the circuit from said source of energy through said first and last mentioned switches to said actuator, as an incident to the falling of live coals from said grate.

CHARLES R. BARNETT.

CERTIFICATE OF CORRECTION.

Patent No. 2,058,945.

October 27, 1936.

CHARLES R. BARNETT.

It is hereby certified that error appears in the printed specification of the above numbered patent requiring correction as follows: Page 2, first column, line 9, for the hyphenated word "circuit-breaking" read circuit-making; and that the said Letters Patent should be read with this correction therein that the same may conform to the record of the case in the Patent Office.

Signed and sealed this 5th day of January, A. D. 1937.
